UNITED STATES PATENT OFFICE.

FRANK DOCHNAL, OF ST. LOUIS, MISSOURI.

MANUFACTURE OF HOLLOW TILE AND THE LIKE.

1,369,522.

Specification of Letters Patent. Patented Feb. 22, 1921.

Application filed May 12, 1919. Serial No. 296,350.

To all whom it may concern:

Be it known that I, FRANK DOCHNAL, a citizen of the United States, residing in the city of St. Louis and State of Missouri, have 5 invented certain new and useful Improvements in the Manufacture of Hollow Tile and the like, of which the following is a specification, the present application being a continuation in part of my application

10 Serial Number 259,921, filed October 28, 1918.

My invention relates to the manufacture of hollow tile, or the like, and more particularly to what is termed as open end tile for 15 use in building smoke-stacks, tanks, silos or similar wall structures.

In the manufacture of open end tile, it is necessary to provide each end of the tile with a temporary end wall tie section to keep 20 the tile from warping while going through the burning process, and, further to prevent unreasonable breakage of the tile in handling and in shipment to a job. In view of this, and in order to enable me to manufacture and use my open end hollow tile patented September 3, 1918, Number 1,277,556 25 it is necessary for me to provide my open end tile with temporary end wall tie sections.

The object of my present invention is to 30 provide the temporary end wall tie sections, of each tile, with a plurality of opposed weakening channels to form thin wall sections at their bases, and to provide these thin wall sections with lines of suitably spaced 35 perforations, or perforations and indentations alternately arranged to weaken the end wall tie sections and permit of their easy removal by a slight tap with a convenient tool after the tile has been burnt so that the tile 40 may be laid into a wall structure in the form of open end tile.

A further object of my present invention is to provide convenient and efficient means for forming the opposed channels in the temporary end wall tie sections, and providing 45 the thin wall section at the base of each pair of opposed channels with a line of suitably spaced perforations, or alternately arranged perforations and indentations to 50 weaken the tie sections so they may be easily broken away without destroying the real ends of the tile.

A further object of the invention is to 55 provide means to provide the end wall tie sections, intermediate each set of opposed

channels, with a line of perforations to further weaken the tie section, when necessary.

A still further object of the invention is to provide suitable guide-plates extending 60 from the tile forming die, to guide and support one or both sides of the temporary end wall tie section while they are being perforated, or alternately perforated and indented.

With these and similar objects in view, the 65 device itself consists in the novel features of construction, combination and arrangement of parts as will be hereinafter referred to and more particularly pointed out in the claims hereto appended.

Referring to the accompanying drawings forming a part of this specification, wherein like characters of reference denote similar parts throughout the several views:

Figure 1, is a front elevation of a forming 70 die, showing my invention applied to one side thereof, the other side being partly removed to clearly show the face and form of the die.

Fig. 2, is a top plan view, partly in section.

Fig. 3, is a side elevation of the device.

Fig. 4, is a detail showing one of the guide plates in side elevation.

Fig. 5, is a detail in perspective of one 85 of the guide plates.

Fig. 6, is a detail of a tile, showing a part of one of the end wall tie sections partly broken away, to provide an open end tile.

Fig. 7, is a front elevation of a forming 90 die showing a modified form of device positioned adjacent thereto.

Fig. 8, is a top plan view thereof, partly in section.

Fig. 9 is a detail of a tile, showing a part 95 of one of the end wall tie sections partly broken away, to provide an open end tile.

Referring to the drawings, the reference character 1 designates a suitable clay receiving cylinder, while 2 designates the 100 plunger, and 3 the soft clay.

In carrying out the aim of my invention, I employ a suitable die 4 and suitably fix the same to a clay receiving cylinder 1. I have clearly shown in Fig. 1, a die provided with clay passages 5 suitable for forming a tile of the shape shown in my Patent Number 1,277,556, dated September 3, 1918, but so formed as to provide this particular tile 105 with end wall tie sections 6, shown in the 110

present drawings, for temporarily uniting the end walls thereof, while burning same, to prevent warping of the end walls and to prevent breakage of the tile in shipment.

5 In order to properly guide and support the end wall tie sections 6 of the tile, after they pass through the clay passages 5 of the die 4, and to provide the inner and outer faces of the tie sections 6 with weakening 10 channels 7 and 8, respectively, I employ suitable guide plates 9 provided with a plurality of channel forming ribs 10, which ribs are spaced apart to form the passages 11 between adjacent ribs 10, as clearly shown in 15 Fig. 5. These ribs 10 may be formed in the die, if desired, so as to extend into the clay passages 5, as is manifest.

It will be here observed from Fig. 6, of the drawings, that a thin clay wall section is 20 formed at the base of each pair of opposed channels 7 and 8, which are preferably rectangular in form.

The guide plates 9 are suitably fixed to the die 4, in such a manner that the ribs 10 25 will extend into the clay passages 5 of the die. Each guide plate 9 is provided with a plurality of cutaway portions 12, to receive rotary disk perforators, or perforators and indentors to be hereinafter described, and 30 with a plurality of weakening channel cleaning teeth 13. The guide plates 9, extend forward from the die, as clearly shown in Figs. 2 and 4.

Rotatably supported, by means of suitable 35 supporting brackets 14, and the pivot pin 15, are a plurality of disk perforators and indentors 16. For convenience only, I have shown the use of three rotary disk perforators and indentors 16 positioned on opposite 40 sides of a clay tile 17 emerging from the die 4. These disks 16 are each provided with a plurality of relatively long radially extending 45 perforating arms 18, and intermediate each pair of arms 18 a relatively short groove forming arm 19 is positioned. The long arms 18 are adapted to pass clear through the thin sections of the end wall tie sections 6 and form slotted perforations 20, while the short arms 19 merely form indentations or 50 short grooves 21 therein, as clearly shown in Figs. 2 and 9. These disks 16 will be known as the outer perforators and indentors.

I further provide the device with what 55 will be known as inner perforators 22, which perforators are rotatably supported by means of suitable brackets 23, and the pivot pins 24. The brackets are suitably fixed to and supported by the die 4, and extend 60 forward from the die 4, as shown in Figs. 1 and 2. The perforators 22 are provided with but one shape of perforating teeth 25 which are all of the same length to provide the end wall tie sections 6 with slotted perforations 26, intermediate the rows of alter-

nate perforations 20 and indentations 21, as shown in Fig. 3. These perforations 26 further weaken the tie sections 6, as is manifest. The teeth 25 of the rotary perforators 22 pass through the slotted openings 27 of the inside guide plates 10. If desired, it is of course understood, that rotary disks like the outside disks 16 may be employed as inside perforators and indentors, it merely depending upon how weak 70 the end tie wall sections can be made without warping while they are being burnt.

A perforator cleaning device, such as a suitable hair brush 28 may be rotatably supported by means of a suitable bracket 29 and pivot pin 30 adjacent each outer rotary disk perforator and indentor 16. I have only shown one of these cleaners, in the drawings, but it is obvious that one may be positioned adjacent each set of perforators, if deemed necessary, to remove sticky clay 85 therefrom. These brushes may be power driven, if desired.

While the operation of the herein-described invention is obvious from the drawings and specification, it will be clearly understood, that the moving clay formed into tile shape in passing out of the die, will impart a rotary motion to the several rotary elements 16 and 22, as the tile is 90 forced forward, and that the arms 18 and 19 of each rotary element 16, will perform their duty of alternately perforating and indenting the end wall tie sections 6 from the outside of the tile, while arms 25 of each 100 rotary element 22 will perform their duty of slotting or perforating the end wall tie sections 6, intermediate the rows of perforations 20 and indentations from the inside of the tile. 105

It will be observed, that the temporary end wall tie sections 6 for tile that are channeled, perforated and indented, as herein described, may be easily removed after the burning of the tile, by a slight tap with a 110 suitable tool.

As is obvious, the perforations and indentations formed in the wall of the tile, by the rotary elements, may be in straight lines, staggered, or in any other manner, or formation desired. The perforations may be of any size, or shape, likewise the indentations. 115

It will be understood that as many rotary elements may be employed, as desired, and 120 that one or all four bars of a tile may be channeled and perforated, or perforated and grooved at the same time, as is manifest.

It will be here understood that I may, if desired, provide one or more faces of a tile 125 with a line, or lines of perforations 20 only, and omit the indentations 21, by the use of suitable rotary elements, or vice-versa.

From the foregoing description, it is clear that the channels 7 and 8 will save clay in 130

the manufacture of the tile, and permit the perforators to pierce through a thinner body of clay.

When the inside perforators 24 are not employed, it is obvious, that the outside guide plates 9 may be removed. In this case, if the outside face of the tile is to be channeled, the ribs 10 may be made a part of the die, as is manifest, or the outside plates 9 may be shortened, so as not to extend beyond the ribs 10 thereof.

The many advantages of the herein described invention will readily suggest themselves to those skilled in the art to which it 15 appertains.

I do not desire to be understood as limiting myself to the details of construction and arrangement as herein described and illustrated, as it is manifest that variations and 20 modifications may be made in the features of construction and arrangement in the adaptation of the device to various conditions of use without departing from the spirit and scope of my invention and the 25 terms of the following claims, hence wish it to be understood that I reserve the right to make any such changes or modifications as may fairly fall within the scope of the appended claims when fairly construed.

30 What I claim is:

1. The herein described method of making hollow tile which is to be finally used as open end tile, which consists in forcing clay through a die, providing a temporary end 35 wall tie section, or sections of the tile with a plurality of lines of slotted perforations for weakening the end wall tie section, or sections so they may be easily broken out by the tap of a convenient tool after being 40 burnt and prior to being laid into a wall structure.

2. The herein described method of making hollow tile which is to be finally used as open end tile, which consists in forcing clay 45 through a die, providing a temporary end wall tie section of the tile with a plurality of weakening channels, progressively forming one or more lines of alternately arranged slotted perforations and indentations in the 50 end wall tie sections in the path of the channels, progressively forming a line of slotted perforations between adjacent lines of alternately arranged slotted perforations and indentations and then finally scraping the 55 weakening channels to clean them of clay accumulations.

3. A continuous tile forming device adapted to convert a substantially continuous mass of soft clay into hollow tile with 60 temporary end wall tie sections, in combination, with means for alternately perforating and indenting the temporary end wall sections of the tile as it leaves the forming device to substantially weaken and lighten the 65 temporary end wall sections so that they

may be broken away after the tile has been burnt to provide an open end tile.

4. A continuous tile forming device adapted to convert a substantially continuous mass of soft clay into hollow tile or the 70 like of specified length, comprising tile-forming means adapted to progressively shape the clay into hollow tile or the like, in combination, with means for alternately perforating and indenting one or more walls of 75 the tile as it leaves the forming device.

5. The process herein described of making hollow tile, which consists of forcing clay through a forming die, and providing one or more walls of the tile with one or more 80 lines of alternately arranged perforations and grooves for weakening the wall or walls of the tile to permit part or all of the wall being easily removed without destroying the remainder of the tile.

6. In combination, of a clay forming die having means to form weakening channels in a wall or walls of a tile being formed, rotary elements positioned in the path of travel of the tile in such a manner that the 90 emerging tile will impart motion to the rotary elements and cause the rotary elements to alternately perforate and impress a groove in a section of a wall or walls of a tile to weaken same so that the weakened section 95 can be easily broken away, after the tile has been burnt without destroying the adjacent wall sections of the tile.

7. In combination with a tile forming machine having a forming die through which 100 clay is to be forced to form a hollow tile with at least four solid walls, guide plates extending from the die, channel forming ribs arranged on the plates, rotary elements having alternately arranged radially extending 105 perforating and indenting arms supported in advance of the die in such a manner that the moving clay in the form of a tile will rotate the rotary elements and provide a wall or walls of a tile with a line or 110 lines of alternately arranged perforations and indentations from the outside of the tile, rotary elements having radially extending perforating arms supported in advance of the die in such a manner that the moving tile will rotate the said rotary elements and provide a wall or walls with a line of 115 perforations between adjacent lines of alternately arranged slotted perforations and indentations, and channel scraping means 120 carried by said guide-plates.

8. In combination with a tile forming machine having a forming die through which clay is to be forced to form a hollow tile with at least four solid walls, guide plates 125 extending from the die to guide the walls to be perforated, channel forming ribs arranged on the plates, rotary disks having alternately arranged radially extending perforating and indenting arms supported in 130

- advance of the die in such a manner that the moving clay in the form of a tile will rotate the rotary disks and provide a wall or walls of a tile with a line or lines of 5 alternately arranged perforations and indentations from the outside of the tile, rotary disks having radially extending perforating arms supported in advance of the die, in such a manner that the moving tile will 10 rotate the said rotary disks and provide a wall or walls with a line of perforations between adjacent lines of alternately arranged slotted perforations and indentations, channel scraping means carried by said guide plates and means for cleaning said rotary disks of clay accumulations.
9. In combination with a hollow tile forming machine having a forming die to provide open end tile with temporary end wall 20 tie sections, of rotary means to perforate the temporary end wall tie sections so the same may be easily broken away after being burnt without destroying the end walls of the tile.
- 25 10. In combination with a hollow tile forming machine having a forming die to provide open end tile with temporary end wall tie sections, of rotary means to alternately perforate and indent the temporary 30 end wall tie sections so they may be easily broken away after being burnt without destroying the permanent end walls of the tile.
11. In combination with a hollow tile forming machine having a forming die to provide open end tile with temporary end wall tie sections, of means for forming the 35

temporary end wall sections with a plurality of opposed channels to form thin wall sections, and means for providing said thin 40 wall sections with suitably spaced perforations.

12. In combination with a hollow tile forming machine having a forming die to provide open end tile with temporary end 45 wall tie sections, of means for forming the temporary end wall sections with a plurality of opposed channels to form thin wall sections, means for providing said thin wall sections with suitably spaced perforations, 50 and indentations, alternately arranged.

13. In combination with a hollow tile forming machine having a forming die to provide open end tile with temporary end 55 wall tie sections, of means for forming the temporary end wall sections with a plurality of opposed channels to form thin wall sections, means for providing said thin wall sections with suitably spaced perforations, and guide plates for guiding and supporting 60 temporary end wall tie sections while they are being perforated.

14. In combination with a hollow tile forming machine having a forming die to provide open end tile with temporary end 65 wall tie sections, of plates extending from the die to guide the temporary end wall tie sections after leaving the die, and means for weakening the temporary end wall tie sections while being guided and supported 70 by said plates.

In testimony whereof, I have hereunto signed my name to the specification.

FRANK DOCHNAL.
